UNITED STATES PATENT OFFICE

2,550,081

AIR-HEATING FURNACE AND HOLLOW
BAFFLE STRUCTURE THEREFORClifford Wade Nesbitt, Kalamazoo, Mich., as-
signor to Borg-Warner Corporation, Chicago,
Ill., a corporation of Illinois

Application April 26, 1947, Serial No. 744,097

11 Claims. (Cl. 126—110)

1

The present invention relates generally to warm air heating furnaces, and it has more particular reference to an improved furnace radiator baffle arrangement.

The present invention contemplates a warm air heating furnace which is adapted for installation in a minimum of space especially a restricted space such as may be present in certain utility units which are installed in pre-fabricated and the smaller types of houses. A utility unit is a compact arrangement which contains therein facilities for coupling the numerous fixtures of the kitchen, laundry and bathroom spaces of a house, and occupies a comparatively small space, having a cross-sectional area approximately $3\frac{1}{2} \times 7\frac{3}{4}$ feet and usually extends from the floor to the ceiling. Such units are factory assembled and are shipped complete to the location of the building being constructed. A region in a utility unit is allotted to the heating equipment or furnace, and while said equipment may occupy a definite proportion of the cubage of said unit, nevertheless the furnace must be of minimum dimensions. Hence the furnace must be of an efficient type and be so constructed that there is a maximum of heating surface within a constricted or minimum of space.

While the present furnace arrangement is primarily intended for use in a utility unit as above suggested, it is not limited to such use and it is well adapted for installation in a cellar or other space in a house for the purpose of heating the rooms thereof.

The present invention contemplates the provision of a warm air heating furnace fabricated from sheet metal plates so as to comprise a suitable combustion chamber and effective means for heating air. In lieu of the usual exterior heat exchange radiator, there is a novel baffle arrangement between the combustion chamber and smoke outlet to materially increase the length of travel of the ignited gases or hot products of combustion from the fire pot beneath the combustion chamber and to raise the temperature of air being heated.

It is one of the principal objects of this invention to simplify the construction of a warm air heating furnace, such as contemplated herein, and to improve the efficiency and operation of such furnace.

2

Another object hereof resides in providing a warm air furnace which includes a sheet metal casing, having a generally rectangular form, the rear wall of which has the usual chimney outlet, and spaced from this rear wall by a plurality of vertically arranged baffles, is a combustion chamber which is defined by the front and side walls of said casing and one of said baffles.

Still another object resides in the provision of a hollow baffle unit which extends between the top, bottom and side walls of the furnace body, the hollow portion of said baffle defining an air duct which extends through openings in the top and bottom of the furnace body. It is here noted that this novel baffle is employed in lieu of the usual radiator which is hung on the outside of the customary warm air furnace body.

The present baffle is formed of two identical metal plates which are welded together into a unitary assembly thereby adapting the structure for economical manufacture. Also the baffles are so constructed that they are reversible when being installed, that is, one baffle, which is the first baffle is placed in one position and the next or second similar baffle which is spaced from the first baffle is up-ended or inverted. In this manner the direction of travel of the hot gases is reversed at each baffle and an elongated heating surface is established which is to be contacted by air being heated.

Additional objects, aims and advantages of the present invention will be apparent to persons skilled in the art after the construction and operation of the heating furnace and radiator baffle arrangement is understood from the within description.

It is preferred to accomplish the numerous objects of this invention, and to practice the same, in substantially the manner hereinafter fully described and as more particularly pointed out in the appended claims. Reference is now made to the accompanying drawings that form a part of this specification.

45 In the drawings:

Fig. 1 is a vertical side elevation partly broken away, of a warm air heating furnace assembly such as contemplated herein.

Fig. 2 is an enlarged side elevation, partly 50 broken away, of the furnace body showing the

radiator baffles, the combustion chamber, and the fire pot.

Fig. 3 is a vertical section taken transversely through the furnace body along the plane of line 3—3 on Fig. 2.

Fig. 4 is a plan of the furnace body with the rear portion of the top broken away.

Fig. 5 is a perspective view showing one of the stamped sheet metal plates used in fabricating the novel baffle contemplated herein.

Fig. 6 is a fragmentary detail view.

The drawings are to be understood as being more or less of a schematic character for the purpose of disclosing a typical or preferred form of the improvements contemplated herein, and in these drawings like reference characters identify the same parts in the different views.

Referring first to Fig. 1, it will be seen that the furnace assembly A is mounted on a hollow base B of generally box-like form which has a skeleton frame comprised of vertical and horizontal angle metal strips 10, 10, which is closed by vertical walls 11 and has an open front 12. Within this hollow base there is a suitable blower 13, having an upwardly pointing discharge nozzle 13a to direct extraneous air upwardly toward the furnace body and into air ducts of the baffles, as will be later explained herein. Immediately back of the open front there is a conventional air filter 14 through which air is drawn into the base through the open front 12 by means of the blower 13. It is contemplated, however, that the front may be closed and an air ingress opening made in the bottom or another wall with the air filter back of such opening. The base B may rest upon the floor, although it is preferred that the entire furnace structure be supported on angle pieces forming the framework of a utility unit such as hereinbefore mentioned.

The furnace assembly A embodies an outer shell of box-like form which comprises a plurality of horizontal and vertical angle metal strips 16, 16, forming a skeleton frame the vertical portions of which are closed by panels 16a. The shell has an open top 16b and there is a relatively large opening in its bottom which communicates with the hollow base B through which the blower nozzle 13a protrudes so that the air current created by the blower is directed upward past the furnace body to be heated and is then discharged through open top 16b into a plenum chamber or other structure for distribution to the rooms.

The furnace body C of box-like form is supported in any suitable manner within the hollow shell, and connected to its lower region there is a fire pot 17. In the arrangement shown in Fig. 1 the fire pot is supplied by a conventional oil burner 18a, while in Fig. 2 a gas burner 18 is shown, it being understood that either type of fuel may be used in the furnace contemplated herein.

The furnace body is comprised of a plurality of vertical walls or panels 19, the rear wall having a flanged smoke outlet or aperture 20 for discharging the products of combustion into a pipe 21 leading to a chimney or other flue. The top 22 of the furnace has downturned flanges fitted over the upper margins of the vertical walls, and has a plurality of slot-like rimmed openings 23 extending transversely across the panel forming the top. The bottom 24 has upturned flanges overlapping the vertical walls, and has slot-like rimmed openings 25 transversely of the panel aligned vertically with openings 23 in the top.

In the oil burning furnace shown in Fig. 1

(detailed in Fig. 6), there is a large circular opening 26 in the bottom 24 with an outwardly flanged throat 27 in which the cylindrical fire pot 17 is received. A perforate ignition chamber 17a is supported in the fire pot and has an open top through which the flames pass upward into the combustion chamber 28 comprising the forward or front region of the casing or housing as will be seen by reference to Fig. 1. In the gas burner type shown in Fig. 2, the fire pot 17 has a slightly different contour than that used with the oil burner, and in lieu of the circular flanged-throat the bottom wall has its front portion cut away to provide a large opening 26a of preferably rectangular contour.

It is contemplated that the panels defining the vertical walls, as well as the top and bottom of the furnace, be fabricated from heavy sheet metal plates of a suitable gauge and welded together to provide air-tight and gas-tight joints or seams. These plates may be economically produced by any well-known stamping method and when assembled they provide the body of the furnace into which the hot ignited gases pass from the burner through the bottom opening to rise and expand in the combustion chamber 28.

As hereinbefore stated, an important feature of this furnace resides in providing novel baffling means encompassed within the walls of the furnace, said baffling means being constructed in a manner so that air being heated passes through said baffling means from the exterior of the furnace beneath the bottom 24 and will be discharged in a heated state through the slot-like openings 23 in the top 22. The baffles, for the sake of economy, as well as for the purpose of providing an efficient air heating means, are made of identical sheet metal stampings, two of which are united by welded seams. These baffles are set upright in parallel spaced relation to each other, and entered from side to side and from the top to the bottom of the furnace body C. The exterior contour of a baffle is such that in structures where two baffles are used as shown herein, one baffle may be arranged in an inverted position with respect to the other baffle thereby providing a circuitous path which effects a lengthening of the distance traveled by the ignited gases and products of combustion to the discharge opening 20.

Since the baffles are identical it will be sufficient to describe one structure in detail. A baffle comprises a sheet metal plate D having a generally rectangular form as shown in perspective in Fig. 5, the metal plate being stamped to define therein a channel which extends longitudinally of the plate. This provides an elongated shallow dished portion 29 extending from end to end of the plate. At the longitudinal rims of this dished portion 29 there are elongated fins 30 which are in the normal plane of the plate, and it will be seen that these fins extend unbroken to one end of the baffle plate D while at the other end of the plate said fins have recessed regions 31, which are made by cutting away portions of the plate so that when the baffle is installed in the furnace these recesses 31 provide transverse passages for permitting the travel of the hot products of combustion past the baffle. The margins of fins 30 have elongated lateral flanges 32 and at one end of the plate the fins which are not cut away, there are short flanges 33. The channel or dished portion 29 has ends formed in a bottleneck manner to provide constricted

regions 34 at the inlet and discharge ends of each baffle unit.

After plates D have been formed as shown in perspective in Fig. 5, two of such plates are placed in superimposed relationship, and since they are identical, the fins 30 will lie in intimate surface contact with each other and are arranged with their recessed portions 31 in registry at one end of the baffle. The fins are then welded in any suitable manner, preferably by a continuous seam, to provide a gas-tight and unitary assembly. The two channeled or dished portions of the plates together define air ducts E longitudinally through the baffles for the air being heated.

The front baffle, which is in a position farthest from the smoke outlet 20, is placed close to the upper rear edge of fire pot 17 so that it provides the rear wall of the combustion chamber 28. This front baffle is mounted in an upright position in the casing or housing with its recessed portions 31 uppermost or at the top of the furnace body. The lateral flanges 32 and 33 of this remote baffle rest against the inner surfaces of the vertical walls 19 and the bottom 24. The next or intermediate baffle is set upright in the casing between the first baffle and the back or rear wall of the casing, but it is arranged in inverted position, with the recessed portions 31 of the fins lowermost or at the bottom of the furnace body. This second or intermediate baffle is secured to the walls of the casing by welding or otherwise in the same manner as described with reference to the first or remote baffle. The ends of the dished portions of the baffles preferably project through the rimmed openings 23 and 25 in the top and bottom of the casing as clearly shown in Figs. 1 and 2, and since the parts of each baffle are assembled by a welding seam on the fins leakage of gas into air-ducts of the baffles is prevented.

The ignited products of combustion from the fire pot and burner will rise in the combustion chamber 28 and will travel to the top thereof where they find egress past the adjacent baffle through the recesses or passages 35 which are formed on each side of the upper portion of said baffle by the recessed portions 31 of the fins. These hot products of combustion must then travel downward between the two baffles as shown by the arrows (Fig. 2), and then through the passages 35a at the bottom of the inverted rear baffle, after which the products of combustion travel upward and then pass out of the furnace body through the smoke or discharge outlet 20 to the chimney or the flue.

It will be seen that while the furnace is comparatively small in cubage there is an extremely long travel of the products of combustion entirely within the confines of the furnace body, due to the baffle arrangement, thereby materially slowing down the velocity of these combustion gases so that considerable heat is absorbed therefrom by the metal plates forming the baffles. Also the plates forming furnace body C become quite hot by contact with these hot gases and hence are raised to a high temperature.

The blower 13 in the base section B creates a current of filtered air which is directed upwardly against fire pot 17 and around the walls of furnace body C, and also a portion of this air enters the inlet necks 34 at the bottoms of the baffles. This air current travels upwardly in the air ducts E and expands in the wide regions of said ducts. The bottleneck arrangement tends

to hold back the air being heated within the baffles so that said air will absorb a considerable portion of the heat units by intimate contact of the metal surface by the air ducts. Any desirable arrangement may be made for the distribution of the heated air after it reaches the top of the shell from around furnace body D as well as the hot air which is emitted from the discharge throats of the baffles.

10 The bottleneck shape of the baffle unit air ducts is one of the important features of this invention because it increases the efficiency of heat extraction. The air to be heated, entering the larger region of the air ducts expands and increases in volume because of the heat absorbed by it, and the restricted outlets retard the flow of air, thus tending to increase the air contact time and the heat transfer. The arrangement of this furnace enables the condensing of a maximum heating surface into a comparatively small unit and avoids the use of the usual large exterior radiator employed in heating furnaces of the warm air type generally in use.

15 While this invention has been described in detail in its present preferred form or embodiment, it will be apparent to persons skilled in the art, after understanding the improvements, that, various changes and modifications may be made therein without departing from the spirit or 20 25 30 scope thereof. It is aimed in the appended claims to cover all such changes and modifications.

What is claimed is:

1. In a space heater and the like a plurality of sheet metal walls defining a closed hollow casing, one of said walls having an outlet aperture; a plurality of structurally independent spaced baffles arranged transversely in the portion of said casing adjacent said apertured wall and extending to the side walls of said casing, 35 the baffle which is farthest from said apertured wall together with the other casing walls defining a combustion chamber; means supplying ignited gases to the lower region of said combustion chamber; said baffles being cooperatively associated with each other and with the casing walls for directing the products of combustion in a circuitous path in transit from said combustion chamber to said outlet aperture; said baffles being of hollow section to define air ducts 40 45 50 55 60 65 70 75 extending through the upper and lower casing walls and being adapted to pass extraneous air upwardly through said casing whereby said air is heated by the products of combustion moving through said circuitous path; the ends of said baffles having restricted throats defining inlet and discharge regions adapted to retard passage of extraneous air therethrough; recessed regions adjacent the ends of said baffles defining passages for products of combustion past said baffles; and means for creating an air current directed towards the inlet regions of said air ducts.

2. In a space heater and the like comprising a plurality of sheet metal walls defining a closed hollow casing, one of said walls having an outlet aperture; a plurality of structurally independent elongated spaced baffles arranged transversely in the portion of said casing adjacent said apertured wall and extending to the side walls of said casing, the baffle which is farthest from said apertured wall together with the other casing walls defining a combustion chamber; means supplying ignited gases to the lower region of said combustion chamber; said baffles being of

hollow section for defining air ducts therethrough, said hollow baffles extending through the upper and lower casing walls and being adapted to effect the flow of extraneous air upwardly through said casing whereby said air is heated by the products of combustion moving through said circuitous path; said baffles at the sides of said air ducts defining longitudinal side fins extending to opposite side walls of said casing, said fins having alternately arranged interrupted regions adjacent the upper and lower chamber walls whereby the products of combustion are directed in a circuitous path through said chamber to said outlet; and means for creating an air current directed to the inlet regions of said baffle air ducts.

3. As a new article of manufacture, a baffle for warm air furnaces and the like, said baffle having an air duct therein and being formed of two identical sections, each said section comprising a sheet metal plate having a generally rectangular shape; a shallow depressed region offset laterally from the plane of said plate, said depressed region extending from end to end of said plate between the sides thereof and having end portions of less width than its intermediate region; the portions of said plate lying alongside the rim of said depressed region defining oppositely projecting longitudinal fins; and lateral flanges at the margins of said fins; said two sections being arranged with said fins in contacting relation to each other and secured together by a gas-tight joint with the depressed regions of the two plates facing each other thereby to define the aforesaid air duct in said baffle.

4. As a new article of manufacture, a baffle for warm air furnaces and the like, said baffle having an air duct therein, comprising a sheet metal plate having a generally rectangular shape; a longitudinal open channel formed in said plate between its sides, said channel extending from end to end of said plate and having constricted end regions; oppositely projecting longitudinal fins along the rims of said channel, said fins being interrupted at a side of one of said constricted end regions; and closure means extending across said channel and secured to the portions of said plate alongside said channel, whereby to define the aforesaid air duct through said baffle.

5. As a new article of manufacture, a baffle for warm air furnaces and the like, and having an air duct therein which is characterized by a bulged central portion and restricted end portions, said baffle comprising a sheet metal plate having a generally rectangular shape; a shallow depressed region offset transversely from the plane of said plate, said depressed region extending from end to end of said plate between the sides thereof and having portions at each end of less width than its intermediate region, said end portion defining between them said bulged central portion; oppositely projecting longitudinal fins along the longitudinal rims of said depressed region; and a sheet metal closure plate secured to said fins in bridging relationship to said depressed region, whereby said two plates define the aforesaid air duct through said baffle.

6. A baffle member for retarding discharge of hot products of combustion from a furnace of the warm air type and adapted for installation in the furnace between the combustion chamber and the smoke outlet, said baffle member comprising two identical sheet metal plates hav-

ing generally rectangular contour, each plate being formed with a longitudinal channel extending from end to end thereof with a wide intermediate region; flat regions at the sides of said channel; said plates being arranged in superimposed relation with said flat regions contacting each other and anchored together by welding, said channels together defining a longitudinal duct with a wide expansion chamber and restricted end regions for passage through said baffle of extraneous air to be heated, the portions of said plates which define said channels being adapted to separate the air being heated from the hot products of combustion in transit to the smoke outlet of the furnace.

7. A baffle member as defined in claim 6 wherein the end regions of said channels are of less cross-sectional area than the intermediate regions whereby to retard passage of air through said baffle.

8. A baffle member as defined in claim 6 wherein the flat regions of the plates define fins which are recessed adjacent one end for passage of products of combustion outside of and past the baffle member.

9. A baffle member as defined in claim 6 wherein the channels are constricted at each end, and the flat regions have recesses proximate one end for passage of products of combustion outside of and past the baffle member.

10. A space heater and the like comprising, a plurality of sheet metal walls defining a closed casing having an outlet in one wall; a plurality of structurally independent upstanding baffles arranged in separated spaced order in the portion of said casing adjacent said outlet wall, one of said baffles and said outlet wall defining a combustion chamber; means supplying ignited gases to the lower region of said combustion chamber; each baffle comprising a sheet metal plate of generally rectangular shape; a longitudinal open channel between the sides of said plate and extending from end to end thereof, the end regions of said channel being shaped to define restricted throats; oppositely projecting fins along the longitudinal rims of said channel, and closure means extending across said channel and secured to said fins thereby to define an air duct through said baffle; said air ducts extending through upper and lower walls of said casing and being adapted to pass extraneous air through said casing to be heated in said ducts by the products of combustion moving through a circuitous path; and recessed regions at the end of alternate baffles alongside said throats defining passages for products of combustion to travel in a circuitous path past said baffles to said outlet.

11. A space heater comprising a plurality of sheet metal walls defining a hollow body having a combustion chamber at one end region and an outlet at the opposite end region; and a heat exchanger in said hollow body comprising horizontally spaced elongate tubular members of flat cross-sections defining vertical baffles having air ducts therein, the forward one of said baffles being adjacent said combustion chamber and defining a wall thereof, and another of said baffles being adjacent said outlet; constricted throats at the end regions of said hollow baffles; fins projecting outward along the longitudinal edges of said baffles and being attached to side walls of said hollow body, said fins extending continuously from one end of each baffle and being interrupted adjacent the opposite end of such baffle; said interrupted fin portions being

alternately arranged respectively at the upper and lower regions of successive baffles whereby said baffles define a circuitous path for the flow of hot gases from said combustion chamber and past said baffles to said outlet, the throats of said baffles extending through the top and bottom walls of said hollow body; and means for directing extraneous air to the lower inlet regions of said baffle air ducts whereby such extraneous air is heated in transit through said ducts in intimate association with the hot gases flowing in said circuitous path from the combustion chamber past and around said baffles to said outlet.
